to retard or prevent direct passage of water from the outside to the inside of the garment.

It is a feature of the invention that the suit is an integral unit arranged to completely cover the body except for the hands and face so that there is no necessity for looking for various parts of clothing when an alarm is sounded and the fireman is in a hurry to answer it.

It is to be understood that a suit of this kind may be worn not only by firemen but by fishermen, letter-carriers and all persons compelled to be outdoors during rainy days.

The garment may be of any size and may be provided with any desired ornamentations. The garment may be of colored fabric and any number of colored combinations.

The slide fastener may be of any conventional construction also of a concealed type to make it invisible from the outside and make the joining more waterproof.

While I have shown and described the preferred embodiment of my invention, it is to be understood that I do not limit myself to the precise construction herein disclosed and the right is reserved to all changes and modifications coming within the scope of the invention as defined in the appended claim.

Having thus described my invention, what I claim as new, and desire to secure by United States Letters Patent is:—

A water-proof suit for firemen and others, comprising water-proof and heat-proof material in the form of a suit having a body portion, arm portions, leg portions and boot portions all connected to an integral unit, said body portion being formed with an opening extending down from the neck at the front to the vicinity of the crotch, said arm portions being formed with openings extending in from the free ends thereof, and means for holding each of said openings closed, comprising hook fasteners along the edges of said opening and a control slide for engaging and disengaging said hooks from each other, and shield strips behind said openings permanently attached along one of their edges upon the material of the suit on one side of the openings and detachably connected with the material of the suit on the other sides of the openings, each detachable connection comprising a snap device formed from wires so as to be flexible and adapted to have two parts coacting, one attached permanently upon the shield strip and the other part permanently attached upon the material of the suit.

FREDERICK G. MOLTER.
